UNITED STATES PATENT OFFICE

2,108,833

TELEGRAPHIC KEYING CIRCUIT

James D. Wallace, Washington, D. C.

Application July 22, 1930, Serial No. 469,899

2 Claims. (Cl. 250—17)

(Granted under the act of March 3, 1883, as
amended April 30, 1928; 370 O. G. 757)

My invention relates broadly to signaling systems and more particularly to a telegraphic keying circuit for signaling systems.

One of the objects of my invention is to provide a simplified circuit arrangement for a telegraphic keying circuit in a signaling system having means for suppressing the key clicks normally offering objectionable interference in nearby receivers by the reproduction of noises in the nature 10 of "thumps".

Another object of my invention is to provide an electron tube circuit arrangement for a modulation system in a telegraphic transmitter having means for preventing abrupt changes of 15 potential of the grid with respect to the cathode for eliminating key clicks in the transmitted signals.

Still another object of my invention is to provide an arrangement of screen grid tube circuit 20 including a filter circuit adapted to suppress key clicks during rapid telegraphic modulation of a signal transmitter.

Other and further objects of my invention will be understood from the specification hereinafter 25 following by reference to the accompanying drawing in which:

Figure 1 shows a telegraphic modulation circuit embodying the principles of my invention; Fig. 2 illustrates a modified form of keying circuit having means for suppressing key clicks; Fig. 3 shows a further arrangement of keying circuit which may be employed according to my invention; Fig. 4 shows a noise suppressing circuit connected in the keying system according to a 35 further modified form of my invention; and Fig. 5 illustrates another modified arrangement of circuit for eliminating key clicks according to my invention.

Referring in detail to Fig. 1 of the drawing, 40 the keying circuit of my invention includes a screen grid electron tube indicated by reference character 1 having cathode 2, control grid 3, plate electrode 4, and screen grid 5. The input circuit is indicated at 6 containing a source of sustained oscillations 7. The tuned output circuit is shown at 8. The cathode 2 is heated from suitable source 2a. The plate potential is fixed by battery 17 and the screen grid potential is fixed by a tap 18 on the battery 17. By-pass condensers 19 and 20 are arranged around the battery 17 and the tapped sections thereof. The battery 9 is provided for supplying bias potential. Reference character 10 indicates a potentiometer composed of two resistances 10a and 10b. Reference character 11 45 indicates a keying resistor, and 12 shows the key.

The keying action is obtained as follows: When 12 is open, the voltage of the control grid 3 with respect to the cathode 2 is equal to the battery voltage 9. This should be great enough to block the tube. When 12 is closed, resistance 11 is 5 paralleled with part of the potentiometer 10. Under this condition, the control grid is connected across part of the potentiometer 10 instead of the entire battery, and the negative control grid potential with respect to the cathode 10 is decreased. In this manner the transmitter is decreased. In this manner the transmitter may be telegraphically keyed according to the signaling code. The condenser 14, and resistance 15 cooperate in suppressing the key clicks. Some rectified grid current will flow through the 15 resistor 15, but this has no effect on its action of removing key clicks. Before the grid potential with respect to the filament may be changed, a certain quantity of electricity must flow either into or from the condenser 14, depending on 20 whether the control grid potential with respect to the cathode is raised or lowered. Since no electrons flow from the control grid to filament during the proper operation of an amplifier, it is obvious that the charging or discharging condenser current must flow through resistance 15. 25 It may be shown from the laws of the electric circuit that under the above conditions the voltage across the condenser 14 will not change instantaneously, but will require a certain period of 30 time for its potential to change. Since this condenser 14 is directly across the cathode and control grid of the amplifier, and assuming that the generator 7 has a low impedance to waves produced by keying disturbances, then the potential 35 of the grid with respect to the cathode will not change as abruptly as it would, if the condenser 14 and resistance 15 were omitted. Very objectionable key clicks are produced by the circuit of Fig. 1 if the condenser 14 and resistance 15 are 40 omitted.

Another method of keying sometimes used in connection with screen grid tubes consists of alternately applying and removing the positive potential from the screen grid. A condenser and 45 resistance may be connected in the circuit of the screen grid to aid in the elimination of key clicks. The circuit shown in Fig. 2 is an example of utilizing capacity and resistance in the screen grid circuit to lessen the effect of key clicks. 50 The keying action of this circuit is as follows: The key 12 when open does not allow any positive potential with respect to the cathode to reach the screen grid 5, and experience has shown that when the screen grid potential is 55

removed from a screen grid tube, no electronic current flows from cathode to plate. When 12 is closed, positive potential reaches the screen grid through the resistors 11 and 21, thereby causing plate current to flow. The action of the resistances 11 and 21 and condenser 14 toward the elimination of key clicks is as follows: When 12 is closed, the screen grid potential does not instantaneously rise to its proper value, but the 10 condenser 22 must receive a charge before it assumes the proper potential, and since this charging current must flow through resistance 21, a finite time is required to charge the condenser and consequently, the screen grid cannot 15 assume its proper potential until the condenser 14 is charged. When 12 is opened, before the screen grid loses its positive charge, the condenser 14 must discharge. Since 14 must discharge through the resistance 11 and the resistance 20 of the electronic path from cathode to screen grid, the discharge is not instantaneous, but a finite time is taken for the discharge. Therefore, it has been shown that the use of the condenser 14 and the resistances 11 and 21 cause 25 the change in screen grid voltage not to be abrupt, but cause the change to be gradual. The plate battery 17 need not necessarily be tapped as shown at 18, but a potentiometer may be utilized, or a series resistance of proper value 30 may be used which would enable the entire plate battery 17 to be connected across the circuit supplying the screen grid 5. Key clicks in a five electrode tube may be suppressed in this manner, keying the screen grid, or space charge grid, 35 or both. The circuit will function in connection with certain tubes having a high shield grid to cathode resistance with the resistance 11, short circuited and removed from circuit. The condenser 22 is a radio frequency by-pass from 40 the screen grid 5 to the cathode 2, and has so low a value of capacity, that its effects are inconsequential on the operation of the key click 45 eliminator.

The circuit in Fig. 3 shows another method of screen grid keying with the circuit for the elimination of key clicks. The keying action of the circuit in Fig. 3 is as follows: When the key 12 is open, the proper potential reaches the screen grid through the three resistances 11, 21, and 23, but when 12 is closed the current flows through 50 23 directly to the cathode 1, thereby leaving the screen grid at cathode potential, and the electronic current from cathode to plate then ceases. The total resistance of the three resistors 11, 21, and 23 must be of great enough value to cause 55 enough drop from the screen grid current, so that the screen grid voltage will be of the proper value. Also 23 must be of great enough value to prevent too much drain on the plate supply 60 source 17 when the key 12 is closed. The action of condenser 14 and resistances 11 and 21 as an 65 eliminator of key clicks will be apparent from the circuit arrangement. When key 12 is opened, time is required to charge the condenser 14 through resistances 21 and 23, and therefore the 70 screen grid 5 does not instantaneously get its operating potential. When the key 12 is closed, the condenser 14 then discharges through two paths, 11 and cathode to screen, and 21, and because of the resistance it does not discharge immediately, and therefore the screen grid does not lose its positive potential immediately. It has therefore been shown that the use of the resistances 11 and 21 and the condenser 14 eliminates key clicks by the prevention of very abrupt 75

changes in screen grid potential. The condenser 22 in Fig. 3 has the same function that it had in Fig. 2. The potential supply for the screen grid may be supplied from a tapped battery, or from a potentiometer, instead of from the entire plate battery 17 as shown. Also a five electrode tube may be used in connection with this key click eliminator, keying either screen grid, space charge grid, or both. The circuit shown in Fig. 3 may also have resistance 11 removed and still 10 function properly with certain types of tubes.

There is another method of keying a screen grid tube. Instead of merely removing its positive potential, its potential is changed to negative with respect to the filament to key the output 15 of the transmitter. A method of doing this is shown in Fig. 4. When the key 12 is open, the screen grid obtains its potential from the plate battery through the resistance 21. When 12 is closed the screen grid is connected to the bias 20 battery, and when the screen grid is at a negative potential the electronic flow from filament to plate ceases. But when the screen grid has changed from positive to negative, the condenser 14, since it is connected from screen grid to 25 cathode, has also changed its polarity in like manner. But the charging or discharging current must flow through resistance 11. As a result the condenser charge does not change instantly, but takes a finite time. In this way the screen grid 30 does not change its potential so abruptly, and therefore key clicks are eliminated. When key 12 has been closed, and is then opened, the condenser 14 and resistance 11 act again so as to prevent the change in screen grid potential from 35 being so abrupt. The capacity 22 keeps the screen grid at the radio frequency potential of the cathode, and has so low a value of capacity that it has no effect on the action of the key click 40 eliminator.

A circuit which operates similarly to the circuit of Fig. 4 is shown in Fig. 5. The resistance 11 is located in a slightly different position in the circuit as shown. However, in using this method, 45 11 must have much less resistance than 21, or these resistors may become a potentiometer which may cause the screen grid to have a negative potential not nearly so large as the voltage of battery 9 when the key 12 is closed, and it is possible in certain cases, that the screen grid 50 would be slightly positive under this condition. It is obvious that a five electrode tube could be used in place of a four electrode tube, keying either shield grid or space charge grid, or both.

The values of resistance used in connection with the key click eliminator vary from about 5000 to 20,000 ohms. The capacity used varies from about 0.1 microfarad to 0.5 microfarad. These values given apply to keying systems which are hand operated. Their values must be reduced if 55 high speed automatic keying is used.

The invention herein described and claimed may be used and/or manufactured by or for the Government of the United States of America for governmental purposes without the payment of 60 any royalties thereon or therefor.

While I have described my invention in certain preferred embodiments. I desire that it be understood that various modifications of the circuit arrangement of my invention may be employed and I intend no limitations upon my invention other than are imposed by the scope of the appended 70 claims.

What I claim as new and desire to secure by Letters Patent of the United States is as follows: 75

1. In a telegraphic keying system, an electron tube having a cathode, an anode, a control grid and a screen grid, an input circuit interconnecting said cathode and control grid, an output circuit interconnecting said cathode and anode, a keying circuit comprising a source of potential and three resistors connected in series between said screen grid and said cathode, a key connected to short-circuit one of said resistors and said source, and a condenser connected between said cathode and the terminal remote from said screen grid of the resistor nearest said screen grid. 5
2. In a telegraphic keying system, an electron tube having a cathode, an anode, a control grid and a screen grid, an input circuit interconnecting said control grid and said cathode and comprising a source of biasing potential connected 10

to apply a negative biasing potential to said control grid, an output circuit interconnecting said cathode and anode, a keying circuit comprising a key, a condenser and a resistance connected in series between said cathode and the negative terminal of said source of biasing potential, said screen grid being connected to a point in said keying circuit on the side of said condenser remote from said cathode, and a source of potential and a resistor connected in series between said cathode and said screen grid for applying to said screen grid a potential positive with respect to said cathode but of magnitude smaller than said source of biasing potential, whereby during keying said screen grid alternately has positive and 15 negative potential with respect to said cathode.

JAMES D. WALLACE.
